UNITED STATES PATENT OFFICE.

ARRIGO VARETONI, OF CLIFTON, NEW JERSEY.

CHECK PROTECTOR.

Application filed October 9, 1924. Serial No. 742,697.

To all whom it may concern:

Be it known that I, ARRIGO VARETONI, a subject of the King of Italy, and a resident of Clifton, in the county of Passaic and State of New Jersey, United States of America, have invented a new and Improved Check Protector, of which the following is a full, clear, and exact description.

This invention relates to check protectors and more specifically to an attachment for check books which facilitates the inking of the finger to provide finger prints on the check and also includes means whereby the finger may be readily cleaned after the finger printing operation.

An object of the invention is to provide an improved attachment which includes an inking pad, a compartment containing a cleansing material, a tongue for removable attachment to the cover of a check book, an improved means for folding a hinged cover over the pad and cleaning chamber, and an improved construction or shape of cover for facilitating the tearing of checks.

In general, the primary object is to provide a simple form of attachment for check books which includes convenient means for finger printing checks.

With these and other objects in view the invention consists in certain novel features of construction and combinations and arrangements of parts as will be more fully hereinafter described and pointed out in the claims.

In the accompanying drawings—

Figure 1 is a plan view showing an open check book with my improved attachment in position, the cover of the attachment being open and broken away.

Fig. 2 is an exaggerated view in longitudinal section on the line 2—2 of Fig. 1, the cover being shown in closed position.

Fig. 3 is an enlarged plan view of the attachment illustrating the same in position for tearing a check.

1 represents an ordinary check which, in the present instance, is illustrated as the upper check of a series and is bound in a cover 2 in any ordinary manner.

50 A represents my improved attachment which comprises a relatively flat metal casing 3. In one end thereof an inking pad 5 is located and in the other end, a perforated compressible tube 7 containing a

cleansing compound 6 is provided. The 55 tube 7 is flat and its perforated upper wall is easily depressed so that the composition will be exuded when pressure is applied.

8 represents a cover for both chambers and is hingedly connected at one end as 60 shown at 9 and provided with a spring 10 which tends to open the cover. This cover is provided on its under face with a hook 11 normally engaged by a spring arm 12 constituting a catch to hold the cover in 65 closed position. This arm projects beyond the side of the closed cover so that it is in a convenient position for movement to release the cover, and when this operation takes place the spring 10 will swing the 70 cover to open position. The cover is preferably formed with a straight edge 13 with an angular edge 14 at one end so that a check containing amounts can be readily torn off, using the cover as a straight edge 75 as indicated in Fig. 3.

In order to conveniently attach the device to the check book a relatively long, preferably spring tongue 15 is fixed to the bottom of casing 3 and may be projected between 80 thicknesses of the binding cover 2 so that when the checks are exhausted the attachment may be removed from the check and a new check book inserted. I also preferably include as a part of the apparatus a sheet 85 of blotting paper 16 which may be inserted under the casing 3 and be in convenient position for drying the finger after it has been subjected to the cleansing composition.

The invention is, of course, not limited to 90 any particular manner of placing the finger prints on the checks as this may be left entirely to the discretion of the user.

Various slight changes might be made in the general form and arrangement of parts 95 described without departing from my invention and hence I do not limit myself to the precise details set forth, but consider myself at liberty to make such changes and alterations as fairly fall within the spirit 100 and scope of the appended claims.

I claim:

1. An attachment of the character described comprising a casing, an inking pad in the casing, and cleansing means on the 105 casing.

2. An attachment of the character described comprising a casing, an inking pad

in one end of the casing, and a perforated compressible receptacle adapted to contain cleansing material in the other end of the casing.

5 3. An attachment of the character described comprising a casing adapted to contain an inking pad, a hinged cover on the

casing, a spring tending to open the cover, a catch holding the cover in normal closed position, and a tongue fixed to the casing and adapted for removable attachment to the cover of a check book. 10

ARRIGO VARETONI.
